DESIGN FOR A CONTAINER FOR
POKER CHIPS

Joseph Foier, Brooklyn, N. Y.

Application September 14, 1946, Serial No. 133,323

Term of patent 14 years

(Cl. D34—5)

To all whom it may concern:

Be it known that I, Joseph Foier, a citizen of the United States and a resident of Brooklyn, county of Kings, and State of New York, have invented a new, original, and ornamental Design for a Container for Poker Chips, of which the following is a specification, reference being had to the accompanying drawing, forming part thereof.

Figure 1 is a perspective view of a container for poker chips in closed condition, showing my new design;

I claim:

The ornamental design for a container for poker chips, substantially as shown.

JOSEPH FOIER.
